UNITED STATES PATENT OFFICE.

ROY MORRIS ALLEN, OF EAST ORANGE, NEW JERSEY, ASSIGNOR TO WESTERN ELECTRIC COMPANY, OF NEW YORK, N. Y., A CORPORATION OF ILLINOIS.

TELEPHONE-SUPPORT.

1,088,669.

Specification of Letters Patent.

Patented Feb. 24, 1914.

Application filed July 18, 1911. Serial No. 639,101.

To all whom it may concern:

Be it known that I, ROY MORRIS ALLEN, citizen of the United States, residing at East Orange, in the county of Essex and 5 State of New Jersey, have invented a certain new and useful Improvement in Telephone-Supports, of which the following is a full, clear, concise, and exact description.

This invention relates to improvements in 10 movable apparatus such as is used to support telephones and similar structures in convenient, adjustable positions for use.

The objects of the invention are to simplify the apparatus, to increase its durability, and to reduce the cost of manufacture.

The apparatus employs a radial arm supported at one end, its free terminal moving in a curvilinear path, like the arc of a circle; the telephone or other structure is located 20 at the free end of this arm, and when moved as described is maintained in a substantially unvarying angular position with respect to a normal plane, such as a horizontal plane. The arm referred to is composed of two parallel members sliding on each other, or reciprocating; near the terminals their adjacent contact surfaces are toothed and there are two toothed disks between the two members, one at each end of the arm; these 25 toothed disks mesh with the cogged members of the arm. There is a strap or series of straps, or a casing, uniting the two members constituting the described arm; this holds the two members in reciprocating position 30 with respect to each other. One toothed disk is fixed on a stationary support, the other toothed disk is supported by the two members constituting the arm and, in turn, supports the telephone or other similar 35 structure. A spring is provided to neutralize the action of gravity on the arm, so that it may occupy any radial position until 40 positively moved.

The accompanying drawings illustrate the 45 invention.

Figure 1 is a side elevation of the device with one of the plates at the upper end of the arm broken away to show the pinion in mesh with the racks and the spring casing 50 removed from the bracket at the lower end of the arm to show one of the counter-balancing springs. Fig. 2 is a plan view of the lower supporting plates with the arm and casing broken away to show the springs.

Fig. 3 is a section on line 3—3 of Fig. 1. 55 Fig. 4 shows the racks of the arm meshing with the stationary pinion at the lower end thereof, and Fig. 5 is a section in perspective through the plates at the lower end of the arm, showing the manner of supporting the 60 pinion thereon.

The arm *a* is composed of two slidably related members 10 and 11 held in engagement by means of the straps 12 which are secured to the member 11 by means of the 65 rivets 13. These straps have loops or eyes 14 through which the flexible conductor 15 passes from a point in the supporting base *b* to the transmitter *t* at the free end of the arm *a*. The adjacent portions of the bars 70 10 and 11 at each end thereof are cut away and provided with the racks 16. Positioned between the opposing racks 16 at the opposite ends of the arm *a* are the pinions *c* and *d*, respectively.

Rotatably secured to the base member *b*, as at 20, is a bracket consisting of the spaced parallel plates *e*. Each of these plates is provided with an aperture corresponding in contour to the pinion *c* and in which the 80 said pinion is non-rotatably mounted. The pinion *d* is supported between the plates *g* in much the same manner as pinion *c* is secured to the plate *e*, with the exception that only one plate *g* receives a toothed portion 85 of the pinion, as clearly shown in Fig. 3. Extending through the pinion *c* is a pin 40, the projecting ends of which are loosely surrounded by collars 8. Each of the plates *e* is provided with an arcuate slot 27 through 90 which projects a pin 26 carried by the arm 11. This slot and pin limits the movement of the arm *a*. Each of the plates *e* is provided with a series of openings 25. Coiled about each of the collars 8 is a spring 23 95 having one end secured to the pin 26 and the other end turned at an angle and inserted in one of the openings 25. The springs 23 are inclosed by the casing caps 21 and 22, which are retained in position by means of 100 the screws 9 inserted therethrough into the ends of the pin 40. Pivotally secured to the plates *g* is a bracket *h* to which the telephone standard may be secured in any desired manner.

When the telephone is moved upwardly or downwardly, the bars 10 and 11 slide one on the other. On the downward movement the

105

bar 11 moves outwardly and the bar 10 moves inwardly, and on the upward movement the reverse takes place. This movement is due to the pinion *c* being fixed to the plates *e* and operates to always maintain the telephone standard in a position perpendicular to the supporting surface for the base member *b*.

The force which must be exerted on the arm *a* to counter-balance the action of gravity varies from a minimum when the arm is in its uppermost position, to a maximum when the arm is horizontal. As the arm is moved upwardly, the pin 26 approaches the pinion *c*, thus decreasing the effective leverage of the spring 23. At the same time the opposite ends of the springs approach each other, whereby the tension of the spring is diminished. These two factors coöperate to increase or diminish the amount of compensating action of the springs as the arm is raised or lowered. Thus by placing the angular end of the spring 23 in different apertures 25, the tension of the spring can be so adjusted as to accurately counter-balance the weight of the arm *a* in whatever position it may be placed, so that said arm will remain in any angular position to which it may be moved.

I claim:

1. The combination with a vertically movable member to be supported in unvarying relation to a normal plane, of a base and a pair of parallel slidably related supporting arms, racks carried by each of said arms adjacent to the ends thereof, a pair of devices between said arms intermediate the ends thereof, operatively engaging said racks, one of said devices being fixed to the base and the other of said devices being secured to the movable member.

2. The combination with a vertically movable member to be supported in unvarying relation to a normal plane, of a base and a pair of parallel slidably related supporting arms having opposing recesses at each end thereof, a pair of devices between said arms, said devices having lugs engaging said recesses, one of said devices being fixed to the base and the other of said devices being secured to the movable member.

3. In a support for maintaining a structure in unvarying relation to a normal plane during movement thereof in a curvilinear path, the combination of a pair of members having adjacent toothed surfaces, means for maintaining said members in longitudinally reciprocating relation; a pair of toothed disks engaging said toothed surfaces at each terminal of said arms, a rigid support for

one of said disks and a structure supported on the other disk.

4. The combination with a movable structure to be supported in unvarying relation to a normal plane, of a pair of parallel toothed members, a device uniting said members in sliding relation with respect to each other, a pair of toothed disks located between said members, one at each end thereof, means for holding one of said disks rigidly, and a structure supported on the other of said disks.

5. The combination with a movable structure to be supported in unvarying relation to a normal plane, of a pair of parallel toothed members, a device uniting said members in sliding relation with respect to each other, a pair of toothed disks located between said members, one at each end thereof, means for holding one of said disks rigidly, a structure supported on the other of said disks, and means for balancing the action of gravity on said members and supported structure.

6. In a telephone support, a base, a plate secured to said base, a pin projecting from said plate, an arm mounted for rotative and longitudinal movement relative to said pin, and means for compensating for the action of gravity on said arm, consisting of a spring having one end fixed to said arm and the other end fixed to said plate.

7. In a telephone support, a base, a plate secured to said base, a pin projecting from said plate, an arm mounted for rotative and longitudinal movement relative to said pin, and means for compensating for the action of gravity on said arm, said means consisting of a spring coiled about said pin, said spring having one end fixed to said arm and the other end adjustably secured to said plate.

8. In a telephone support, a base, a bracket secured in reto, a pin carried by said bracket, an arm pivotally supported on said pin to move in a vertical plane, a spring for compensating for the action of gravity on said arm having one end attached to said arm and the other end to said plate, and means for causing longitudinal movement of said arm as it is moved upwardly, whereby the point of attachment of said spring to said arm is caused to approach said pin.

In witness whereof, I hereunto subscribe my name this 17th day of July A. D., 1911.

ROY MORRIS ALLEN.
